UNITED STATES PATENT OFFICE.

WILLIAM H. WALKER AND JAMES F. WALKER, OF GATE CITY, ALABAMA.

DESIGN FOR A MANTEL.

SPECIFICATION forming part of Design No. 35,983, dated July 29, 1902.

Application filed May 17, 1902. Serial No. 107,879. Term of patent 7 years.

To all whom it may concern:

Be it known that we, WILLIAM H. WALKER and JAMES F. WALKER, citizens of the United States of America, residing at Gate City, county of Jefferson, and State of Alabama, have invented a new, original, and ornamental Design for Mantels, of which the following is a specification.

In the accompanying drawings, Figure 1 represents the mantel in front elevation. Fig. 2 is a transverse sectional and vertical elevation of the same.

The pilasters *a* have beveled outer edges, and the plinths *b* have their upper portions molded.

c is the mantel-board, having the molded edging *d*.

e is the frieze, *f* the grounds, and *g* a raised panel having a continuous concave beveled border *g'*. In the center of this panel is a check-block *h*, placed in relief and having intagliated lines *i*. These lines *i* are drawn diagonally from side to side of the check-block, forming a square, in the center of which is mounted a rosette *j*.

k k are the brackets, molded at the top and

bottom and having continuous concave beveled borders upon which the shelves *l l* are placed. These shelves support the ornamenteally-turned columns *m m*, which have 30 deep channels or grooves *n n*, arranged above and below the channels *o o* and between the same. Between the channels *n* and *o* the intermediate surface of the column is curved convexly in cross-section and beveled slightly 35 toward the deeper channels.

Near the tops of the columns *m m* a double bead *p p* is provided.

The edges of the frieze and grounds are molded, as shown in the drawings. 40

What we claim, and desire to secure by Letters Patent, is—

The ornamental design for a mantel, as herein described and shown.

In testimony whereof we have hereunto set 45 our hands in presence of two subscribing witnesses.

WILLIAM H. WALKER.
JAMES F. WALKER.
